UNITED STATES PATENT OFFICE.

WILLIAM F. SAWADSKI, OF CHARLESTON, SOUTH CAROLINA.

TUBE EXPANDER.

Application filed January 31, 1921. Serial No. 441,344.

To all whom it may concern:

Be it known that I, WILLIAM F. SAWADSKI, a citizen of the United States, residing at 22 Laurens St., Charleston, in the county of 5 Charleston and State of South Carolina, have invented new and useful Improvements in Tube Expanders, of which the following is a specification.

In the present construction of expanders 10 for the tubes of marine boilers, a conical drill which is freely movable longitudinally through the open end of the stock contacts with rollers and the rapid turning of the stock by a suitable machine forces the conical member outward of the stock and consequently projects the expanding rollers. No means is provided for adjusting the conical member, and aboard vessels where suitable machines for operating such expanders 15 are not installed, these tools cannot be used successfully even when the tube is to be expanded at the upper end thereof and cannot be used at all when the tube is to be expanded at its lower end.

20 It may therefore be considered the primary object of the present invention to produce a tube expander having means for projecting the roller expanding elements through the stock to any desired degree, and 25 whereby the expander may be successfully employed either in an upright vertical position, a downright vertical position, or at any desired angle with respect to the arrangement of the tubes to be expanded.

30 The foregoing, and other objects which will appear as the nature of the invention is better understood, may be accomplished by a construction, combination and operative association of elements, such as is disclosed 35 by the drawings which accompany and which form part of this application.

In the drawings:—

Figure 1 is a plan view of the improvement.

45 Figure 2 is a sectional view on the line 2—2 of Figure 1.

Figure 3 is a transverse sectional view on the line 3—3 of Figure 2.

Figure 4 is a similar sectional view on the 50 line 4—4 of Figure 1.

Figure 5 is a transverse sectional view on line 5—5 of Figure 2. Figure 6 is a similar sectional view on line 6—6 of Figure 2.

Figure 7 is a view looking toward the 55 headed end of the outer portion of the stock which carries the expanding rollers.

Figure 8 is a similar view looking toward the head on the other section of the stock.

Figure 9 is a perspective view of the cone-shaped roller projecting pin.

The stock of my improvement comprises two sections, which, for convenience in manufacture, and also for convenience in assemblage of parts, is constructed of two sections. The outer and longer section is indicated by the numeral 1, and the inner and shorter section is indicated by the numeral 2. As in the general construction, the confronting ends of the sections 1 and 2 are provided with rounded enlargements forming the 70 same with heads 3, the said heads designed to abut and are connected together by removable means such as headed bolts 4.

The inner section 2 is provided with a widened portion which extends longitudinally from its head 3, the said portion being indicated by the numeral 5. The head 3 of the section 2, and its enlargement 5 have a rounded pocket 6 therein, and the inner wall 7 provided by the pocket is bored longitudinally to provide three equi-distantly spaced rounded openings 8 that communicate with elongated slots 9 in the said section 2. The slots 9 terminate away from the outer end of the section 2, and the opposed walls provided by the slots are rounded inwardly in correspondence to the opposed walls provided by the respective openings 8. The openings 8 and the slots 9 communicate with the central rounded bore 10 of the section 2, and 80 passed through each of the openings and entering each of the slots is a roller expanding element 11. The slots and openings are so arranged that the rollers 11 may project into the bore 10, when the outer surfaces thereof are in a line with the outer surface or periphery of the section 2.

The rounded head 3 of the section 2 is peripherally formed with a continuous groove 12, and the rounded head of the section 1 is provided with a peripheral flange 13 that is designed to be received in the groove 12, when the sections 1 and 2 are assembled. The section 1 is provided with an elongated bore 14 extending through the head thereof 105 and terminating a suitable distance from the outer and squared end 15 of the said section. The bore 14 registers with the bore 10.

To retain the expanding rollers 11 in the pockets provided by the slots and openings, I arrange in the pockets 6, over the inner and rounded ends of the said rollers, a bearing

washer 16. Over this washer, I position a sleeve 17. This sleeve is retained in proper position through the medium of comparatively small bolts 18 that pass transversely 5 through the enlargement 5 and have their threaded ends received in threaded openings in the sleeve.

The stock of the tool is provided with an elongated slot 19. This slot is disposed in a line with the end wall of the bore 14 of the section 1, passes through the heads of both 10 of the sections and terminates a slight distance inward of the inner wall 7 provided by the pocket 6.

Arranged for slidable movement through 15 the bore of the stock is a conical pin 20. On the widened end of this pin which is received in the section 1 of the stock, I secure a handle member 21 which is substantially V-shaped in plan whereby the reduced portion 20 thereof, which is connected to the pin, may freely slide through the elongated slot in the stock. The handle 21 may be adjusted to move the pin longitudinally and the said 25 pin contacting with the expanding rollers will force the same outwardly through their slots to properly bear against the tube to be expanded.

Through centrifugal force, incident to the 30 rapid revolving of the stock the pin will automatically be moved outwardly of the said stock to project the rollers when the improvement is held at a downward vertical or at a downward angle slightly beyond the 35 vertical, but the degree in which the rollers are projected may be readily regulated by arranging the head of the pin at any desired

position on the stock. It should have been stated that the elongated slot in the stock has its walls disposed at opposite inclinations, 40 corresponding to the angle sides or edges of the head, and the contacting engagement of the head with the said walls will hold the pin when the latter is retained at said positions, and this is most especially true when 45 the improvement is employed for expanding tubes that are disposed horizontally or at varying angles below the horizontal, as the frictional engagement between the handle and the walls of the slots is sufficient to prevent the pin being moved longitudinally by centrifugal force.

Having described the invention, I claim:—

In a tube expander, a stock having a bore 55 therein, elongated slots whose opposed side walls are rounded inwardly and which provide pockets thereby, expansion rollers freely seated in the pockets, a conical pin movable longitudinally in the bore for contacting with the rollers and projecting the 60 same, said stock having an elongated slot therein arranged between the inner terminal of the bore and inwardly of the rollers, and the longitudinal walls provided by the slot being arranged at opposed angles, and a sub- 65 substantially V-shaped head on the widened end of the pin projecting through the slot and whose angle side surfaces of which are designed to frictionally engage with either of the angle walls provided by the slot, when 70 the stock is revolved, as and for the purpose set forth.

In testimony whereof I affix my signature.

WILLIAM F. SAWADSKI.
